ENVELOPE FOR METALLIC OBJECTS

James Edwin Myers, St. Mary's, Ontario, Canada,
assignor to Globe Envelopes Limited, Toronto,
Ontario, Canada, a corporation of Ontario

Application July 15, 1943, Serial No. 494,830
In Canada January 12, 1943

2 Claims. (Cl. 229—68)

This invention relates to a method of packaging objects to prevent rusting as well as the package in which the object is placed.

In order that a clearer understanding of the invention may be had it may be explained that certain automotive and machine parts and other metallic objects are commonly shipped in paper containers in the nature of a bag or envelope on which can be printed the description of the object with directions for its installation and/or use, the maker's name and other desired information. It is likewise common to treat these parts or objects alone before packing with rust-resisting solution containing grease or oil. In practice it has been found that on arrival at a distant destination or after storage for a period of time, this solution or oil coating, where the object or part has been in contact with the container, has been absorbed by the paper and that at such places of contact oxidation or rusting occurs which, in the case of automotive parts such as piston rings and other objects machined to a high tolerance, rendered them useless as not being capable of installation or interchangeability in the position or for the purpose intended.

The practice of using oiled or greased paper for such containers and inserting therein by hand the parts or objects after they had been treated or dipped in a rust-resisting solution has also proved unsatisfactory in that oxidation or rusting develops at the points of contact on the object by the fingers of the person handling and packing them.

Therefore, one of the principal objects of my invention is to provide an improved method and means whereby such metallic objects can be inserted into convenient paper containers and thereafter dipped into and removed from a rust-resisting solution so as to (1) effectually coat the object with such solution without handling; (2) simultaneously coat the paper of the container with such solution sufficiently to ensure that the points of contact in the interior of said container shall not absorb or withdraw from the coated object the rust-resisting solution so applied to its surfaces; and (3) drain away upon removal of the package from the solution all surplus thereof which if left in the paper container would cause it to burst in packing or to rot in shipping or storage.

A further object of my invention is to provide convenient means for suspending the paper packages or containers in the process of dipping into the rust-resisting solution and/or after removal therefrom so as to ensure such drainage.

Other objects will be in part obvious from the annexed drawing and in part hereinafter indicated in connection therewith by the following analysis of the invention.

This invention accordingly consists in the features of construction, combination of parts and in the unique relation of the members and in the relative proportioning and disposition thereof, all as more completely outlined herein.

10 To enable others skilled in the art to fully comprehend the underlying features of this invention, that they may embody the same by the numerous modifications in structure and relation contemplated by the invention, a drawing depicting one form of the invention has been annexed as part of this disclosure, and in such drawing like characters of reference denote corresponding parts throughout all of the views, in which

15 Fig. 1 shows a rear elevation of a single compartment envelope container with the cover flap up or open;

20 Fig. 2 is a rear elevation of a multiple compartment envelope;

25 Fig. 3 is a front elevation of the three compartment envelope container illustrated in Figure 2 with the top flap closed and the whole folded for shipment. The wording is merely illustrative;

30 Fig. 4 is a semi-diagrammatic elevational view showing how the package is suspended to drain.

35 Referring first to Fig. 1 there is shown a single compartment envelope 5 with the flap 6 up and showing segments 7 and 8 cut away at each of the bottom corners to form orifices for the entry into and drainage out of the container of the rust-resisting solution. For suspension of the container a perforation 10 is provided which is cut through the top flap 6 in a position off-center to allow proper drainage through said orifices when the container is suspended in an inclined vertical position by means of a hook or projection 11 passed through the perforation 10 as shown in Fig. 4, perforation 10 can be suitably edged or reinforced for heavy objects as indicated at 12.

40 In Fig. 2 there is shown a multiple compartment container separated by the paper of the front and back of the container or envelope which parts are glued, sewed, or otherwise fastened together between each compartment as indicated by the dotted lines 13. The orifices or cut out segments at each bottom corner of each compartment are indicated at 7'. In this figure there are three perforations 10' in the top flap for suspension, these being placed in such a position off-center of each compartment, when the envelope or container is folded horizontally these perfora-

tions coincide, Fig. 3, and can pass over a hook or projection for the purposes of suspension in such a position as to ensure drainage as shown in Fig. 4.

It is thus seen that the objects of the invention are obtained by utilizing a paper container in the form of an envelope or bag made of paper of sufficient hardness of surface to take a coating of rust-resisting solution without disintegrating. The quality and strength of the paper employed depends on the size and weight of the metallic object and the nature of the solution, and by cutting away segments 7 of both bottom corners of the container there is provided means for the entry of the solution in the process of dipping and for drainage thereafter. To suspend the container packaging the metallic object 14 indicated by dotted lines in Fig. 4 for the purposes of dipping in the rust-resisting solution 15 and/or of suspending the container thereafter in vertical position to permit drainage of the surplus solution, the circular or other suitably shaped hole 10 in the top flap or cover provides a simple and inexpensive means whereby the container can be hung or suspended alone or with other containers of a similar design on the same or similar hooks, rods, or projections.

While my invention and the mode of practising it have been described and exemplified in certain specific forms or manners, it will be obvious that the principles herein disclosed may be varied or embodied in different forms or manners from those described without departing from the spirit of the invention defined in the following claims.

What is claimed is:

1. A flexible container for dipping into a liquid while containing an article for treatment by the liquid, the container comprising a substantially rectangular flat envelope and having one end open substantially throughout the length thereof, a substantially rectangular flap extending the length of the envelope from the open end of the envelope, an off-center perforation in said flap adjacent one of the upper corners, and the bottom of said envelope having a diagonally opposite corner cut away to perforate the pocket of the envelope thereby to permit drainage when the container is removed from the treating liquid.
- 5 2. A flexible container for dipping into a liquid while containing an article for treatment by the liquid, the container comprising a substantially rectangular envelope transversely elongated to several times its length and having one end open substantially throughout the length thereof, the envelope having spaced vertical lines of connection dividing the envelope into pockets of equal dimensions adapted to be folded along said lines of connection, a substantially rectangular flap extending the length of the envelope from the open end of the latter, said folded lines traversing said flap, perforations in said flap, at least two of said perforations being off-center on opposite sides of one of the fold lines, said elongated envelope being cut away at the bottom from each corner to provide openings in the bottom corners of each pocket to perforate the latter thereby to permit drainage when the container is removed from the treating liquid.
